UNITED STATES PATENT OFFICE

MAURICE CONTE, OF OUGREE, NEAR LIEGE, BELGIUM, ASSIGNOR TO SOCIETE ANONYME D'OGREE-MARIHAYE, OF OUGREE, NEAR LIEGE, BELGIUM, A CORPORATION OF BELGIUM

DIFFERENTIAL PRESSURE GAUGE

Application filed June 29, 1927, Serial No. 202,324, and in Belgium July 14, 1926.

This invention relates to improvements in or relating to differential pressure gauges and is particularly applicable to gas-meters.

A gauge constructed according to the present invention dispenses with the annular float on the bell, and the flexible chain or the like to which the vertical rod, located in the central tube of the bell, is attached, is connected to a pulley which is fixed on the same axis as 10 a cam. A thread is attached to this cam and passes over the surface of same and has a counterweight suspended from its other extremity. The central tube has a rotatable plate, attached to the base thereof, which 15 plate is perforated exactly the same as the base of said tube, hence, by rotating the plate, the area of the holes in the base can be regulated.

This apparatus is practically unaffected by 20 variations of the surrounding temperature and the oscillations in the pressures of the gas may be damped.

In order that the invention may be more 25 readily understood reference may be made to the accompanying drawings in which:

Figure 1 is a schematic section of a gauge constructed according to the present invention.

Figures 2 and 3 are respectively a vertical 30 section and a plan of the central tube of the floatless bell.

A gauge constructed according to the present invention comprises a cylindrical container *a* in which a suitable liquid *b* and 35 the bell *c* dipping into the liquid *b*, are enclosed. At the center of the base of the container *a* is located a mercury reservoir *d*, containing mercury *e* wherein the central tube *f* of the bell *c* is submerged. A rod *g* is secured 40 in any convenient manner to the bottom of the tube *f*, which rod passes through an open tube *h* of the container *a*, one end of which is also submerged in said mercury, and which rod extends upwardly to the exterior of the 45 container *a*. The two different pressures obtained in Venturi or Pitot tubes or a diaphragm, located within the main (not shown in the drawings) through which the gas flows, are transferred to the gauge through 50 pipes *i*, *k* the high pressure pipe *i* leading

into the bell *c* and low pressure pipe *k* leading into the cylinder *a*.

A support *l*, suitably located on the top of the cylinder *a*, carries the spindle *m* to which the pulley *n* and the cam *o* are secured. A 55 thread, chain, or the like *p* is attached to the upper end of the rod *g* and to the pulley *n*. A similar thread or chain *r* is secured to and passes over the surface of the cam *o* and carries at its extremity a counterweight *s*. Said cam *o* has a peripheral cam face having a radially directed surface portion near the cam axis and curving from said cam portion radially away from the axis to the radially outer portion of said cam *o*. 60

In Figure 1 the apparatus is shown in the position it assumes when there is no gas flowing in the main. In this position the turning moment of the counterweight *s* about the center *m* is equal and opposite to the turning moment of the weight of the bell *c* and rod *g* about the center *m*. 65

When gas flows in the main the bell *c* will rise since the pressure of the gas in the bell *c* will be greater than the pressure of the gas in the cylinder *a*. The gradual increase in the difference between these two pressures will be balanced by the corresponding increase in the effective weight of the bell as it rises out of the liquid *b* in the cylinder *a*. This effective weight is also increased owing to the rotation of the pulley *n* and the cam *o* which decreases the turning moment of the counterweight *s*. 70

The spindle *m* may carry a pointer or the like (not shown) which moves over a scale and the cam *o* may be so designed that this scale may have constant dimensions or not as desired and in the latter case the scale may be as described in my above specification. 75

The apparatus for damping the oscillations in the pressures, which may be caused, for instance, by supplying the gas to the reciprocating piston engines, consists of a plate *u* rotatably secured to the bottom *t* of the tube *f*. The bottom of the tube *f* has a series of perforations and the plate *u* has an identical series of perforations *v*. One method of securing said plate *u* to the bottom *t* of the tube consists of screw-threading the low- 80

100

er end of the rod *g*, passing same through *t* and *u* and screwing thereon the nut *w*. The relative position of the movable plate *u* in relation to the fixed part *t* permits the operative area of the perforations *v* to be adjusted, thus allowing the mercury *e* to pass more or less easily and hence forming an apparatus for damping the oscillations of the liquid levels within the gauge caused by the pressure oscillations or pulsations mentioned above.

Having now particularly described and ascertained the nature of this invention and in what manner the same is to be performed, I declare that what I claim is:

1. A differential pressure gauge comprising a closed casing, a liquid partially filling said casing, a bell in said casing and dipping into said liquid, means for admitting two different pressures inside of the casing, one pressure inside of the bell and the other pressure outside of the bell, a rotatably mounted cam formed with a peripheral cam face having a radially directed surface portion near the cam axis and curving from said portion gradually away from the axis to the outer end portion, a counterbalancing weight, flexible means connected to the radially directed portion of the peripheral face of said cam and lying on and extending over said peripheral cam face and connected to said counterbalancing weight, said casing having an opening, and a liquid-sealed motion transmitting device combined with said bell and passing to the outside of said casing for transmitting the motion of said bell to said cam, the liquid seal of said motion transmitting device serving to seal said opening, and said bell and counterbalancing means being so related through the intermediary of said cam that said counterbalancing means will exert its maximum effort in opposition to the weight of the bell when the bell occupies the position imposed on it by the minimum of differential pressure, whereby as said bell moves under the effect of increasing differential pressure and approaches the position imposed on it by the maximum of differential pressure, said counterbalancing means will approach its minimum effect.

2. A differential pressure gauge, comprising a closed casing, a liquid partially filling said casing, a bell in said casing and dipping into the liquid, means for admitting a high pressure inside of the bell and a low pressure outside of the bell and inside of the casing, a rotatably mounted cam, said casing having an opening, a liquid-sealed motion transmitting device combined with said bell and passing to the outside of said casing for transmitting the motion of said bell to said cam, the liquid seal of said motion transmitting device serving to seal said opening, and counterbalancing means for said bell connected

to the cam face near the cam axis and extending over and engaging the cam face and depending therefrom, said bell and counterbalancing means being so related that said counterbalancing means will exert its maximum effort in opposition to the weight of the bell when the bell occupies under the influence of the minimum differential pressure its most immersed position, whereby as the bell rises due to increase in the difference in pressures, the action of the counterbalancing means on the bell decreases, said motion transmitting means being provided with a damper preventing abrupt movements of the bell.

3. A differential pressure gauge comprising a closed casing, a liquid partially filling said casing, a bell in said casing and dipping into the liquid, means for admitting two different pressures inside the casing, one pressure inside of the bell and the other pressure outside of the bell, a rotatably mounted cam, said casing having an opening, a liquid-sealed motion transmitting device combined with said bell and passing to the outside of said casing for transmitting the motion of said bell to said cam, the liquid seal of said motion device serving to seal said opening, and counterbalancing means for said bell, said bell and counterbalancing means being so related through the intermediary of said cam that said counterbalancing means will exert its maximum effort in opposition to the weight of the bell when the bell occupies the position imposed on it by the minimum of differential pressure, whereby as said bell moves under the effect of increasing differential pressure and approaches the position imposed on it by the maximum of differential pressure, said counterbalancing means will approach its minimum of effort.

In testimony whereof, I have signed my name to this specification at Brussels, Belgium, this 17th day of June, 1927.

MAURICE CONTE.
